RING TRAVELER

Thomas B. Hunt, Greenville, S. C., assignor to
 A. B. Carter, Inc., Gastonia, N. C., a corporation
 of North Carolina

Application July 16, 1942, Serial No. 451,137

1 Claim. (Cl. 57—125)

This invention relates to travelers for textile machinery such as spinning frames, twister frames, and the like and more especially to a traveler which is circular throughout its entire length.

Heretofore, it has been a customary construction to provide inturned straight portions or horns on opposed sides of the gap in the traveler. The remaining portion of the traveler, namely the arch, has sometimes been circular and sometimes oval in shape. The function of the horns has been to slidably engage the web and flange portions of the ring upon which the traveler moves and thus prevent the same from becoming detached. After the traveler has been in operation for some time, the horns pit or wear the lower portion of the ring flange and the upper portion of the ring web and make it necessary for the ring to be reconditioned or replaced.

It is an object of this invention to provide a perfect circle ring traveler in which the straight horns are eliminated adjacent the gap in the traveler, but instead the circular arch extends to the traveler terminals along the same radius. This type of construction makes the manufacture of the traveler more economical because it can be formed with more temper and greater hardness, thereby increasing the life of the same. An additional advantage of a perfect circle traveler is derived from the fact that the outer terminal of the traveler does not contact the outside of the ring web while in operation. This feature provides more space for keeping the traveler cool, and also results in less accumulation of lint upon the traveler.

It is another object of this invention to provide a perfect circle ring traveler of the class described which will prevent the yarn from easily becoming unthreaded during a doffing operation regardless of the type of builder motion on the machine. This unthreading is usually produced by the yarn strand as it pulls the traveler upwardly when doffing the textile machine.

Some of the objects of the invention having been stated, other objects will appear as the description proceeds, when taken in connection with the accompanying drawing, in which:

Figure 1 is a plan view of a portion of a spinning rail and associated spinning ring, illustrating my improved perfect circle ring traveler;

Figure 2 is a transverse vertical sectional view taken along the line 2—2 in Figure 1;

Figure 3 is an enlarged sectional detail view similar to the right-hand portion of Figure 2,

and illustrating more clearly the position of the ring traveler while in operation;

Figure 4 is an isometric view of the ring traveler as it appears when in normal position;

5 Figure 5 is an inverted isometric view of the ring traveler.

Referring more particularly to the drawing, the numeral 10 denotes a conventional spinning rail which may be employed on textile machinery such as spinning frames, twister frames, and the like. At spaced intervals along the rail, a plurality of annular spinning rings 11 are inserted, there being only one spinning ring shown in the present embodiment of the invention.

15 Each of the spinning rings is provided with a vertical web 12 and a peripheral flange 14, said flange 14 extending from the outer periphery of web 12 and being adapted to rest upon the top of spinning rail 10.

20 The upper edge of the ring 11 has a horizontal flange 15 which overhangs both sides of the web 11. This flange is employed as a track-way or guide to which my improved perfect circle traveler 16 is detachably secured.

25 During operation a strand of yarn 17 passes downwardly from suitable drafting rolls, not shown, through the traveler 16 and then horizontally onto a rotating bobbin 18. The bobbin 18 is rotated by a conventional mechanism, and 30 as this rotation takes place, the traveler 16 moves around the ring 12 in substantially the position shown in Figures 2 and 3.

35 By referring to Figures 3, 4, and 5, the details of ring 16 are clearly shown. This ring is formed preferably from a flat piece of metal which is bent in the shape of a circle and which has its ends or horns 19 terminating a slight distance apart from each other, thereby forming a gap 20 between the terminals. The metal

40 from which the traveler 16 is made should be highly tempered and hardened, yet it should be sufficiently resilient or spring-like to permit the proximate terminal ends of the same to be sprung apart and permit the traveler to be inserted or removed over the horizontal flange 15 of ring 11.

Particular attention is called to the fact that the terminals or horns 19 are also circular and have the same radius as the remaining arch portion. In other words, instead of having substantially straight inturned horn portions, the terminals have the same curvature as the arch. Grooves 21 are provided near the tips of the horns so that the contacting portion of the horns with the rings will be in the shape of a

rounded bead, thus reducing the friction when the traveler is in motion. The periphery of each rounded bead is somewhat greater than 180 degrees and the longitudinal axes of the beads are substantially parallel to each other. Furthermore the longitudinal axes of the beads are substantially in alinement with the path of travel of the traveler, therefore only tangential contact will be made with the ring as the traveler floats therearound.

As heretofore enumerated, the chief advantages of a perfect circle ring of this type consists in permitting the traveler to move around the ring with less wear, creates less temperature and friction, has greater ventilation between the outer terminal of the traveler and the web of the ring, permits the traveler to ride higher on the ring and thus has a perfect floating motion.

and finally this traveler does not easily become unthreaded while the textile machine is doffed.

In the drawing and specification there has been set forth a preferred embodiment of the invention, and although specific terms are employed, they are used in a generic and descriptive sense only and not for purposes of limitation, the scope of the invention being set forth in the following claim.

10 I claim:

10 A ring traveler having a pair of terminal horns and an arch extending from one horn to the other, all portions of the horns and the arch lying in the same circle and the horns being wholly within and between two parallel planes defining the sides of the arch portion.

THOMAS B. HUNT.
